ATTACHMENT TRAY FOR A CRIB OR THE LIKE

Clara Virginia Eicholtz, Midland, Mich., assignor to The Dow Chemical Company, Midland, Mich., a corporation of Delaware

Filed Aug. 3, 1962, Ser. No. 71,158

Term of patent 14 years

(Cl. D5—2)

FIGURE 1 is an isometric view of an attachment tray for a crib or the like showing my new design;

FIGURE 2 is a front elevational view thereof;

FIGURE 3 is a top plan view thereof;

FIGURE 4 is a side view thereof, both sides being the same; and

FIGURE 5 is a bottom view thereof.

The characteristic features of my design are indicated by solid lines and reside in an attachment tray for a crib or the like which has a front panel with winged ends and a gently concavely curved and flanged upper edge, the side walls and dividers of the tray including gently concavely curved upper edges.

I claim:

The ornamental design for an attachment tray for a crib or the like, as shown and described.
